UNITED STATES PATENT OFFICE.

URIAH McCLINCHIE, OF BROOKLYN, NEW YORK.

HAND-STRAP.

SPECIFICATION forming part of Letters Patent No. 784,696, dated March 14, 1905.

Application filed September 10, 1904. Serial No. 224,009.

To all whom it may concern:

Be it known that I, URIAHS McCLINCHIE, a citizen of the United States, residing at Brooklyn, in the county of Kings and State of New York, have invented new and useful Improvements in Hand-Straps, of which the following is a specification.

My invention relates to certain new and useful improvements in that class of devices known as "hand-straps" and used in street and other railway cars, coaches, and public vehicles as a handhold or support for passengers who are compelled to stand; and my invention consists, essentially, in the employment of a strap bent upon itself to form upper and lower loops, one for engagement by the passenger and the other to suspend the device from the usual hand-strap-supporting rail and a metallic holder of greater width than the strap and positioned over the front of the latter and provided with loops at the upper and lower portions through which the members of the folded strap are passed and brought together and fastened behind the holder, said holder having also outstanding lugs on its back serving as retaining-guides for the advertising card or sheet which is removably inserted in the holder, as I will hereinafter describe and claim.

In the accompanying drawings, forming part of this specification, and in which similar letters of reference indicate like parts in the several views, Figure 1 is a perspective view of a hand-strap embodying my invention. Fig. 2 is a longitudinal sectional view of the same on the line $\alpha\alpha$ of Fig. 1. Fig. 3 is a rear view.

In carrying out my invention I form the hand-strap of any appropriate length and material, leather being preferred because of its universal use for hand-strap purposes. This strap I prefer to form from a single piece of leather sufficiently heavy for the purpose and of such length that when its ends are folded upon the intermediate portion there is produced two loops—namely an upper loop a for suspending the strap from the rail, which usually extends along the side of the upper portion of the car, and the lower loop b , which furnishes the usual handhold for the

standing passenger. The ends of the returned portions of the strap are brought together and made to overlap, and said overlapping portions are then secured to each other and preferably to the intermediate portion of the strap by means of a rivet or other well-known form of fastening.

In connection with the strap I employ a holder B , which in the present case I prefer to make of metal and of a substantially rectangular form, although I do not wish to be understood as limiting the invention to this precise shape. This holder has the general appearance of a narrow open center frame, and its outer face may be given such design and ornamentation as may be desired. The frame may for the sake of economy in cost of production be cast of malleable material, and in its rear is made a recess d of sufficient depth to receive the card or sheet C , which contains the advertising matter and which is slipped in place endwise through the open side e of the holder. The frame is also cast with the inwardly-projecting lugs f on three of its sides and which lugs overhang the recess d and serve as retaining-guides for the card. To compensate for variations in the thickness of cards used and to secure a card in the frame or holder without danger of its accidental removal, I employ supplemental strips g or equivalent wedges which are introduced between the lugs f and the back of the card, and thereby bind the latter firmly in the recessed back portion of the frame. The frame or holder has its opposite portions also cast or made rigid with oppositely-extending rearwardly-inclined loops D , each having a centrally-located cross-bar i dividing the loop into two openings, one for the passage of each of the portions of the folded strap. When the device is assembled as shown in Fig. 2, the cross-bar of the upper loop will by its contact with one of the ends of the folded strap serve as a stop to prevent the frame or holder from being pulled farther down the strap. A rivet placed between the folded portions of the strap at either or both of the points indicated by dotted lines at l will answer the same purpose. The advertising matter is appropriately displayed on the card,

and this and the attractive character of the holder and the position of the same on the hand-strap quickly draw the attention of the traveling public to the advertisement, with 5 the consequent beneficial results.

The device as described is cheaply made and yet is highly attractive, the metal frame or holder being capable of a high finish and contrasting well with the strap. The strap 10 itself is preferably but a single length, returned upon itself and devoid of fastening, except such as may be required to unite the meeting ends of the straps as previously described.

15 Having thus described my invention, what I claim as new, and desire to secure by Letters Patent, is—

1. An improved hand-strap comprising a single piece of material folded upon itself to 20 form upper and lower loops, and a rigid frame or holder over the face of the strap and having loops through which the folded portions of the strap are passed, the folded portions being united to each other behind the holder.

25 2. An improved hand-strap comprising a single piece of material folded upon itself to form upper and lower loops, an open center frame or holder intermediate of the loops and having oppositely-extending loops and cross- 30 bars extending across the last-named loops and dividing the same into separate openings for the respective portions of the folded strap, and a card or like member contained within said holder and exposing its subject-matter 35 through the open center of the holder.

3. An improved advertising hand-strap

comprising a frame or holder having projecting loops at opposite ends said loops each having a centrally-located cross-bar, a strap passed through said loops at one side of the 40 cross-bars and having its ends returned and passed through the loops at the opposite side of the bars, said returned ends being brought together and united, and a card or like member bearing advertising matter and contained 45 in said frame or holder.

4. An improved hand-strap comprising a strap and a frame or holder thereon, and having loops at opposite ends for engagement with the strap, and a card or member bearing 50 advertising matter, said frame or holder having lugs on its back projecting into the open center and serving as retaining-guides for the advertising card or member.

5. An improved hand-strap comprising a 55 strap and a channeled frame or holder thereon and having loops at opposite ends for engagement with the strap, and a card or member bearing advertising matter, said frame or holder having a recessed back and projecting 60 lugs forming retaining-guides for the card or member, and strips insertible between the lugs and back of the card for retaining the card fixedly in position.

In testimony whereof I have hereunto set 65 my hand in presence of two subscribing witnesses.

URIAH McCLINCHIE.
